US0D1088940S

(12) **United States Design Patent** (10) **Patent No.:** **US D1,088,940 S**
(45) **Date of Patent:** **** Aug. 19, 2025**

(54) **JEWELRY ARTICLE**

(71) Applicant: **PARAMOUNT JEWELS, LLC**, New York, NY (US)

(72) Inventor: **Sumay Bhansali**, Scarsdale, NY (US)

(73) Assignee: **PARAMOUNT JEWELS, LLC**, New York, NY (US)

(**) Term: **15 Years**

(21) Appl. No.: **29/951,895**

(22) Filed: **Jul. 11, 2024**

Related U.S. Application Data

(60) Continuation-in-part of application No. 29/925,521, filed on Jan. 24, 2024, now Pat. No. Des. 1,057,593, which is a division of application No. 29/897,322, filed on Jul. 13, 2023, now Pat. No. Des. 1,028,777.

(57) **CLAIM**

The ornamental design for a jewelry article, as shown and described.

DESCRIPTION

FIG. 1 is a front and top perspective view of a jewelry article showing my new design.

FIG. 2 is a bottom and rear perspective view thereof.

FIG. 3 is a front elevation view thereof.

FIG. 4 is a rear elevation view thereof.

FIG. 5 is a left elevation view thereof.

FIG. 6 is a right elevation view thereof.

FIG. 7 is a top plan view thereof; and,

FIG. 8 is a bottom plan view thereof.

The broken lines in the drawings represent portions of the jewelry article that form no part of the claimed design.

The dash-dot-dash broken lines in the drawings represent a claim boundary and form no part of the claimed design.

1 Claim, 6 Drawing Sheets
